SIFTER FOR FLOUR, ETC

Filed Oct. 30, 1930

FIG. 1.

UNITED STATES PATENT OFFICE

ORA N. McCORMICK, OF ALBANY, INDIANA, ASSIGNOR TO McCORMICK BROTHERS COMPANY, OF ALBANY, INDIANA, A CORPORATION OF INDIANA

SIFTER FOR FLOUR, ETC.

Application filed October 30, 1930. Serial No. 492,322.

This invention relates to flour sifters. The purpose of the invention is to provide a sifter in which the mechanism for oscillating and vibrating the sifter basket is simple and inexpensive to construct and can readily be assembled and taken apart. The details of the invention will be clear from the accompanying drawings, in which,

Fig. 1 is a central vertical section through the sifter and part of a flour bin;

Fig. 2 is a section on the line 2—2 of Fig. 1;

Fig. 3 is a bottom plan view of the sifter, the casing being shown in horizontal section; and,

Fig. 4 is a detail perspective view of the cam and tappet member.

Referring to the drawings, *a* represents the sifter, which is shown in Fig. 1 attached to the flour bin *b*. The casing 1 of the sifter is in the form of a hopper, circular in cross-section and having a cylindrical outlet 2 which may be closed by a cap, not shown. Within the casing is a transverse supporting bar 3, the ends 3a of which are overturned and riveted to the casing. The bar lies at one side of the vertical axis of the casing, and to it are secured two spaced arms *c* and *d*, of inverted U-form, each of which extends laterally across said axis and has a downwardly turned end portion on the opposite side of said axis from the supporting bar. Thus, the arm *c* extends upwardly from the bar and has a laterally extending central portion 4 and a depending end portion 5, while the arm *d*, which is within the arm *c*, has a laterally extending portion 6, spaced from the part 4, and a depending end portion 7 parallel with and spaced from the part 5.

The parts 4 and 6 of the arm are perforated and form bearings for a pivot pin 8 which is rigidly secured to a circular sifter basket *e*, at its center. The bar and the end portions of the arms are perforated hori-

zontally and form bearings for a horizontal shaft *f* which extends across the vertical axis of the basket and projects through the casing and which is bent to form a crank arm 9, by which it may be turned by hand.

The inner end of the shaft is threaded

as shown at 10, and where, as usual, the crank is to be turned in the clock-wise direction, this will be a right-hand thread. A cam wheel *g*, having a plurality of equally spaced points 11, and commonly known as a star wheel, is arranged between the depending ends 5 and 7 of the arms *c* and *d*, and is threaded on to the shaft *f*. The edge of the wheel, between successive points, is curved inwardly, as shown at 12. The star wheel is mounted upon the shaft by inserting it between said depending ends and holding it against rotation while the shaft is turned and threaded into it as far as the threads go on the rod, when the wheel locks with the shaft so as to turn with it. To remove the wheel it will be held stationary by hand and the shaft will be turned to unscrew it from the wheel.

The sifter basket comprises a sheet metal support 13, to which the pivot pin 8 is secured, and this support has radially extending arms 13a, the ends of which are secured to a peripheral rim 14 on the basket. A part 15, integral with the support 13, projects downwardly from said support parallel with the end 5 of the U-shaped arm *c*, and this part 15, which may be called a tappet member, has a transverse slot 16, through which the end of the shaft *f* extends, and it also has curved flanges 17, at its edges, opposite said slot. These flanges lie on opposite sides of the shaft and star wheel and are adapted to be engaged alternately by the points on the latter when the shaft is rotated. The inward curvature of the flanges corresponds approximately with the curvature of the concave surfaces 12 on the star wheel. Preferably, the metal along the edges of the slot 16 is flanged outwardly, as shown at 16a, so that a smooth wearing surface will be presented to the threaded portion of the shaft *f* if the latter comes in contact with the edges of the slot.

The shaft normally extends through the slot 16 and this locks the basket to the supporting means so that if the sifter is inverted the basket will not drop out of the casing. If it is desired to remove the basket, the operator will insert his finger through

the bottom of the casing and hold the star wheel stationary while the shaft is turned backwardly far enough to withdraw the inner end of the shaft from the slot 16, when the basket will freely drop out of the casing. If it is desired to remove the star wheel the backward movement of the shaft will be continued until its threaded end has been withdrawn from the star wheel. In normal operation, the star wheel, guided between the ends 5 and 7 of the supporting arms, prevents undue endwise movement of the shaft.

In operating the sifter, the crank is turned in the clock-wise direction and the points 15 on the star wheel, which are preferably five in number, engage the flanges 17 on the tappet member alternately. When the shaft is rotated at a moderate or fast speed these flanges are thrown inwardly against the concave faces 12 on the star wheel and the basket is given a rapid oscillating movement and also a slight upward and downward rocking movement as the points on the star wheel alternately strike downwardly on one of the 25 flanges 17 and upwardly on the opposing flange, the openings in which the pivot pin 8 is journaled being preferably large enough to permit of a slight rocking movement.

What I claim is:

- 30 1. In a sifter, a casing, a support therein having two spaced vertically arranged parts at one side of the vertical axis of the casing, a horizontally arranged shaft having a threaded end extending through said parts, a star wheel between said parts and threaded on to said shaft, a sifter basket having a central depending pin journaled in said support, and a tappet member depending from the basket and having a transverse slot into which 35 the end of the shaft extends and having also flanges at opposite sides of the shaft adapted to be engaged by the points on the star wheel.
- 40 2. In a sifter, a casing, a support therein having two spaced vertically arranged parts at one side of the vertical axis of the casing, a horizontally arranged shaft having a threaded end extending through said parts, a star wheel between said parts and threaded on to said shaft, said wheel having its 45 edge concave between its successive points, a sifter basket pivoted in said support and having a rim and a sheet metal cross-piece connected to said rim, a tappet member integral with said cross-piece and depending adjacent said spaced parts, said member having flanges, at opposite sides of the shaft, convexly curved toward the star wheel and adapted to be engaged alternately by its points.
- 50 3. In a sifter, a casing, a support therein comprising a cross-bar at one side of the vertical axis of the casing and two spaced arms projecting laterally from said bar across said axis and having depending ends at the 55 opposite sides of said axis, a shaft extending through said bar and ends, a star wheel

on the shaft between said ends, a sifter basket, above said support, having a central pivot pin journaled in the laterally extending parts of said arms, and a tappet member depending from the basket adjacent said ends and having abutments at opposite sides of the shaft adapted to be engaged by the points on the star wheel.

4. In a sifter, a casing, a support therein comprising a cross-bar at one side of the vertical axis of the casing and two spaced arms projecting laterally from said bar across said axis and having depending ends at the opposite side of said axis, a shaft extending through said bar and ends, a star wheel on the shaft between said ends, a sifter basket, above said support, having a central pivot pin journaled in the laterally extending parts of said arms, and a sheet metal tappet member depending from the basket parallel with said ends, said member having a transverse slot through which said shaft extends and having abutments at its side edges adapted to be engaged by the points on the star wheel.

In testimony whereof I affix my signature.

ORA N. McCORMICK.
